(57) **CLAIM**

The ornamental design for a display screen with graphical user interface, as shown and described.

DESCRIPTION

FIG. 1 is a front view of a display screen with graphical user interface, showing our new design;

FIG. 2 is a second embodiment thereof;

FIG. 3 is a third embodiment thereof; and,

FIG. 4 is a fourth embodiment thereof.

The outermost broken line showing of a display screen and the other broken lines showing elements of the graphical user interface illustrate portions of the article and do not form part of the claimed design.
